UNITED STATES PATENT OFFICE.

JOSEPH HARRY COOK, OF PADUCAH, KENTUCKY.

PLANT PROTECTOR.

Application filed April 10, 1925. Serial No. 22,171.

To all whom it may concern:

Be it known that I, JOSEPH H. COOK, a citizen of the United States, residing at Paducah, in the county of McCracken and 5 State of Kentucky, have invented a new and useful Plant Protector, of which the following is a specification.

This invention relates to plant protectors to be employed for covering young plants 10 to protect the plants against damage by frost during early plantings.

An important objection of the invention is to provide a protector including a plurality of transparent walls, together with 15 means for connecting the walls to permit them to be readily disconnected to facilitate the transporting and storing thereof.

Another object of the invention is to provide resilient fastening members which may 20 be positioned around the protector to hold the walls thereof together, eliminating the use of screws, clamps or similar fastening means.

A still further object of the invention is 25 to construct a protector which will be substantially triangular in formation to resist wind pressure and insure against the protector being blown over.

With the foregoing and other objects in 30 view which will appear as the description proceeds, the invention resides in the combination and arrangement of parts and in the details of construction hereinafter described and claimed, it being understood 35 that changes in the precise embodiment of the invention herein disclosed, may be made within the scope of what is claimed, without departing from the spirit of the invention.

Referring to the drawing:

40 Figure 1 is a perspective view of a plant protector constructed in accordance with the invention.

Figure 2 is a horizontal sectional view 45 through the device.

Figure 3 is a vertical sectional view through the upper portion of the device.

Referring to the drawing in detail, the device includes a body portion which is substantially triangular in formation and constructed of transparent members 5.

50 In assembling the protector, edges of the members 5 are brought together and held against movement by securing members in-

dicated generally by the reference character 6, it being contemplated to employ two of 55 such securing members, one arranged adjacent to the upper end of the protector and the other arranged adjacent to the lower end of the body portion.

Each of these securing members includes 60 a length of wire indicated at 7, which is formed with loops 8 at its ends, which loops accommodate the hooks 9 of the coiled spring 10 associated therewith so that the coiled spring will act to draw the loops 8 65 of the length of wire, associated therewith towards each other to cause the wire to closely grip the side members of which the body is formed.

The reference character 11 indicates a 70 covering which is formed of fabric material, portions of the covering being brought down over the transparent members of the body portion.

After the members 5 have been set up in 75 the formation of a protector, and the fabric material has been positioned in a manner as shown by Figure 1 of the drawing, the fastening members are placed on the protector.

When the fastening members are positioned, the upper fastening member is positioned over the downwardly extended portions of the covering 11 to hold the covering 80 85 in position.

From the foregoing it will be seen that due to this construction, a protector constructed in accordance with the invention will be readily and easily disassembled and packed for shipment or storing.

I claim:

1. A protector of the class described including a body portion formed of a plurality of transparent side members, fastening members surrounding the side members to hold the side members in upright positions, each of said fastening members comprising a length of wire having loops formed at its ends, a coiled spring having hooks fitted in the loops to connect the ends of the length of wire, and a cover of fabric material adapted to cover the upper ends of the side members.

2. A protector of the class described including a body portion formed of a plurality of transparent side members, a fabric

cover positioned over the upper ends of the transparent side members, and having portions thereof overlapping portions of the side members, and resilient removable fastening members adapted to embrace portions of the side members to hold the side members together, and one of said resilient

fastening members engaging a portion of the fabric cover to hold it in place.

In testimony that I claim the foregoing as my own, I have hereto affixed my signature.

JOSEPH HARRY COOK.
